G. C. GARHART & S. L. YOUNG.

SWITCH

APPLICATION FILED MAR. 6, 1946

1,240,309.

Patented Sept. 18, 1917.

UNITED STATES PATENT OFFICE.

GEORGE C. CARHART, AND STEPHEN L. YOUNG, OF SYRACUSE, NEW YORK, ASSIGNEES
TO SYRACUSE UNIVERSAL MFG. CO., OF SYRACUSE, NEW YORK, A CORPORATION
OF NEW YORK.

SWITCH.

1,240,309.

Specification of Letters Patent. Patented Sept. 18, 1917.

Application filed March 8, 1917. Serial No. 153,450.

To all whom it may concern:

Be it known that we, GEORGE C. CARHART and STEPHEN L. YOUNG, citizens of the United States, and residents of Syracuse, in the county of Onondaga in the State of New York, have invented new and useful Improvements in Switches, of which the following, taken in connection with the accompanying drawings, is a full, clear, and exact 10 description.

This invention relates to certain new and useful improvements in switches or switch locks adapted for application to switches of predetermined construction, as, for instance, 15 a switch commonly used for controlling automobile or gas engine ignition.

The object of the invention is to provide a switch so constructed or so modified in construction as to be operable only by authorized persons equipped with a key peculiarly designed for a single individual switch.

Other objects relate to the details of construction by means of which the primary 25 object is attained in a preferred manner.

In the drawings—

Figure 1 is a plan view of the switch.

Fig. 2 is a section through the switch beneath the plate hereinafter described.

Fig. 3 is a section similar to Fig. 2 taken beneath the disk hereinafter described.

Fig. 4 is a section on line 4—4, Fig. 1.

Fig. 5 is a section on line 5—5, Fig. 1.

Fig. 6 is a section on line 6—6, Fig. 2.

Fig. 7 is a perspective view of the disk.

Fig. 8 is an elevation of a key.

The switch, as shown, comprises a cup-shaped casing —1— of insulating or other suitable material containing stationary contacts —2— and —3— and a movable sliding contact —4— mounted upon a switch member —5—, which member is in turn mounted upon a collar —6—, the collar being rotatably mounted upon a bearing —7— comprising a substantially cylindrical tubular portion —8— and a base —9—, the base being mounted substantially centrally of the casing —1— and secured to the casing in any suitable and well known manner.

The collar —6— in the known switch is provided with grooves —10— diametrically disposed for receiving a suitable key to turn the collar, the switch member, and the movable contact —1—, a known key being pro-

vided with projections adapted to resiliently 55 seat within the tubular portion —8—.

A washer —11— is fitted over the collar —6— and rests upon the upper surface of the switch member —5— and is adapted to space the circular disk —12— from contact 60 with the switch member and with the contacts —2—, the disk being of sufficient diameter to cover the contacts —2— and —4— and its periphery being even and of circular conformation affording no facility for 65 gripping the disk except in the specific manner hereinafter described.

The annular disk —12— is provided with lugs —13—, in this instance diametrically disposed and projecting inwardly and somewhat axially from the inner edge of the disk and adapted to be seated respectively in grooves —10—.

In order to positively hold the disk —12— rigidly secured to the collar —6—, a suitable screw —14— is provided having its screw portion preferably tapered and of a diameter adapted to force its way into and form co-operating threads upon the tubular portion —8— of bearing —7—; the bearing 75 being preferably formed of some soft metal such as copper, while the screw may be formed of hardened metal, such as suitable characters of steel. The screw is provided with an enlarged laterally extending head 85 —15— adapted to contact with the upper surface of bearing —7— and overlie the grooves —10— with lugs —13— therein.

A suitable cap —16— is provided for covering the screw —14— and acting in 90 combination with a plate —17— for inclosing all of the movable portions of the switch.

As shown, the plate —17— is provided with a dished or offset portion —18— of a diameter substantially the same as the diameter of disk —12— to form a chamber 95 between the disk —12— and the offset portion —18— within which key parts, hereinafter described, are adapted to move.

For the purpose of locking the plate 100 —17— to disk —12— when the switch is in neutral position, the disk is provided with a pair of flanges —19— stamped from interior portions of the disk and extending upwardly and inwardly and overhanging 105 the body of the disk, while the plate is provided with coacting return-bent flanges —20— engaging the flanges —19— when the

switch is in neutral position, and preferably, to prevent any rotative movement of the plate, portions 21 are stamped or otherwise pressed out and adapted to engage bosses upon casing 1 to prevent rotative movement in either direction.

5 The disk 12 may be provided with any suitable number, in this instance two, openings 22 adapted to receive projections 23 upon a key 24 to turn the disk and thereby move the switch element 4. The plate 17 is provided with radial recesses 25, the cap 16 being provided with radial recesses 26 adapted to be brought into registration with the recesses 25 to permit the passage of the key through the combined recesses, the key having an end portion 27 adapted to extend underneath the dished portion 18 of the plate to prevent removal of the key 20 except when tilted.

10 The interior of the casing 1 is thereby rendered entirely inaccessible except when the switch shall be moved to closed position by a predetermined key to disengage the 15 interlocking connection of the flanges 19 and 20.

15 The cap 16 preferable has its lower edge flanged outwardly so as to be of greater diameter than the central opening in plate 17, to prevent removal of the cap in assembled condition of the switch.

20 The key receiving openings in disk 12 may be formed at any desired points in the disk and may be of any desired number, thereby permitting the manufacture of an innumerable number of switches each adapted to be operated by a special key of predetermined construction different from the keys adapted for operating the other 25 switches.

25 Although I have shown and described one specific construction and details thereof as perhaps preferable, I do not desire to limit myself to any specific construction, form or arrangement of the parts, as many changes may be made in each and all of the same without departing from the invention as set forth in the appended claims.

30 What I claim is:

1. In a switch a base, a bearing of relatively soft metal mounted on the base, a collar mounted on the bearing, a disk mounted on the collar, and a screw of relatively hard metal secured to the bearing and adapted to form its own co-acting thread in said bearing and operating to hold said disk in position on said collar.

2. In a switch a base, a bearing mounted substantially centrally of the base, a collar mounted on the bearing, a disk mounted on the collar, and a screw having a threaded relation with the bearing and operating to hold said disk in position on said collar.

3. In a switch a base, a bearing mounted

substantially centrally of the base, a collar mounted on the bearing, a disk mounted on the collar, and a screw having a threaded relation with the bearing and provided with an enlarged head overlying a portion of 70 said disk and operating to hold said disk in position on said collar.

4. In a switch a base, a bearing mounted on the base, a collar rotatably mounted on the bearing and provided with a recess, a 75 disk mounted on the collar and having a flange positioned in said recess, and screw means for holding said flange in said recess.

5. In a switch a base, a bearing mounted on the base, a collar rotatably mounted on 80 the bearing and provided with a recess, a disk mounted on the collar and having a flange positioned in said recess, and a screw having a threaded relation with said bearing and provided with a portion overlying 85 said recess.

6. In a switch a base, a bearing of relatively soft metal mounted on the base, a collar mounted on the bearing, a disk mounted on the collar, a screw of relatively 90 hard metal secured to the bearing and adapted to form its own coacting thread in said bearing and operating to hold said disk in position on said collar, a cap covering the 95 screw, and a closure-plate engaged with the cap.

7. In a switch a base, a bearing mounted substantially centrally of the base, a collar mounted on the bearing, a disk mounted on the collar, a screw having a threaded relation with the bearing and operating to hold 100 said disk in position on said collar, a cap covering the screw, and a closure-plate engaged with the cap.

8. In a switch a base, a bearing mounted on the base, a collar rotatably mounted on the bearing and provided with a recess, a disk mounted on the collar and having a flange positioned in said recess, a screw having a threaded relation with said bearing and provided with a portion overlying 110 said recess, a cap covering the screw, and a closure-plate engaged with the cap.

9. In a switch a base, a bearing of relatively soft metal mounted on the base, a collar mounted on the bearing, a disk mounted on the collar, a screw of relatively hard metal secured to the bearing and adapted to form its own coacting thread in said bearing and operating to hold said disk in position on said collar, a cap covering the screw and provided with a flanged base, and a closure-plate having an opening fitting over the cap and of less diameter than the flanged base 120 of the cap.

10. In a switch a base, a bearing mounted substantially centrally of the base, a collar mounted on the bearing, a disk mounted on the collar, a screw having a threaded relation with the bearing and operating to hold 130

- 5 said disk in position on said collar, a cap covering the screw and provided with a flanged base, and a closure-plate having an opening fitting over the cap and of less diameter than the flanged base of the cap.
11. In a switch a base, a bearing mounted on the base, a collar rotatably mounted on the bearing and provided with a recess, a disk mounted on the collar and having a flange positioned in said recess, a screw having a threaded relation with said bearing and provided with a portion overlying said recess, a cap covering the screw and provided with a flanged base, and a closure-plate having an opening fitting over the cap and of less diameter than the flanged base of the cap.
- 16 12. In a switch a base, a bearing of relatively soft metal mounted on the base, a collar mounted on the bearing, a disk mounted on the collar, a screw of relatively hard metal secured to the bearing and adapted to form its own co-acting thread in said bearing and operating to hold said disk 20 in position on said collar, a cap covering the screw, a closure-plate engaged with the cap, key co-acting means in connection with said disk, and slots in said plate permitting passage of a key to said key co-acting means.
- 25 13. In a switch a base, a bearing mounted substantially centrally of the base, a collar mounted on the bearing, a disk mounted on the collar, a screw having a threaded relation with the bearing and operating to hold said disk 30 in position on said collar, a cap covering the screw, a closure-plate engaged with the cap, key co-acting means in connection with said disk, and slots in said plate permitting passage of a key to said key co-acting means.
- 35 14. In a switch a base, a bearing mounted on the base, a collar rotatably mounted on the bearing and provided with a recess, a disk mounted on the collar and having a flange positioned in said recess, a screw having a threaded relation with said bearing and provided with a portion overlying said recess, a cap covering the screw, a closure-plate engaged with the cap, key co-acting means in connection with said disk, and slots in said plate permitting passage of a key to said key co-acting means.
- 40 15. In a switch a base, a bearing mounted substantially centrally of the base, a collar mounted on the bearing, a disk mounted on the collar, a screw having a threaded relation with the bearing and operating to hold said disk 45 in position on said collar, a cap covering the screw, a closure-plate engaged with the cap, and flanges on the disk and plate interlocked when the switch is in neutral position.
- 50 16. In a switch a base, a bearing secured 55 with the cap, key co-acting means in connection with said disk, and slots in the plate and cap adapted to be brought into registration to permit passage of a key to said key co-acting means.
- 55 17. In a switch a base, a bearing secured to the base, a collar rotatably mounted on the bearing, a disk secured to the collar and having key co-acting means, and a closure-plate secured to the base and having an offset portion of a diameter substantially equal 70 to and registering with the disk and provided with slots permitting passage of a key to the key co-acting means.
18. In a switch a base, a bearing secured to the base, a collar rotatably mounted on the bearing, a disk mounted on the collar and having key co-acting means, a screw having a threaded relation with the bearing and adapted to hold the disk in position on said collar, a cap covering the screw, and an annular closure-plate fitting over the cap and having a dished portion forming with the disk a key-receiving chamber.
19. In a switch a base, a bearing secured to the base, a collar rotatably mounted on the bearing, a disk mounted on the collar and having key co-acting means, a screw having a threaded relation with the bearing and adapted to hold the disk in position on said collar, a cap covering the screw, and an annular closure-plate fitting over the cap and having a dished portion forming with the disk a key-receiving chamber, said plate provided with a slot permitting passage of a key into said chamber.
20. In a switch a base, a bearing of relatively soft metal mounted on the base, a collar mounted on the bearing, a disk mounted on the collar, a screw of relatively hard metal secured to the bearing and adapted to form its own co-acting thread in said bearing and operating to hold said disk 95 in position on said collar, a cap covering the screw, and an annular closure-plate fitting over the cap and having a dished portion forming with the disk a key-receiving chamber, said plate provided with a slot permitting passage of a key into said chamber.
21. In a switch a base, a bearing mounted substantially centrally of the base, a collar mounted on the bearing, a disk mounted on the collar, a screw having a threaded relation with the bearing and adapted to hold said disk 105 in position on said collar, a cap covering the screw, and an annular closure-plate fitting over the cap and having a dished portion forming with the disk a key-receiving chamber, said plate provided with registering openings permitting passage of a key into said chamber.
22. In a switch a base, a bearing of relatively soft metal mounted on the base, a collar mounted on the bearing, a disk mounted on the collar, a screw of relatively hard metal secured to the bearing and adapted to form its own co-acting thread in said bearing and operating to hold said 110 disk in position on said collar, a cap covering the screw, and a closure-plate engaged with the cap, and flanges on the disk and plate interlocked when the switch is in neutral position.
23. In a switch a base, a bearing mounted substantially centrally of the base, a collar mounted on the bearing, a disk mounted on the collar, a screw having a threaded relation with the bearing and operating to hold said disk 115 in position on said collar, a cap covering the screw, a closure-plate engaged with the cap, and flanges on the disk and plate interlocked when the switch is in neutral position.
24. In a switch a base, a bearing secured to the base, a collar rotatably mounted on the bearing, a disk secured to the collar and having key co-acting means, and a closure-plate secured to the base and having an offset portion of a diameter substantially equal 120 to and registering with the disk and provided with slots permitting passage of a key to the key co-acting means.

22. In a switch a base, a bearing mounted on the base, a collar rotatably mounted on the bearing and provided with a recess, a disk mounted on the collar and having a flange positioned in said recess, a screw having a threaded relation with said bearing and provided with a portion overlying said recess, a cap covering the screw, a closure-plate engaged with the cap, and flanges on

the disk and plate interlocked when the switch is in neutral position.

In witness whereof we have hereunto set our hands this 22nd day of February, 1917.

GEORGE C. CARHART,
STEPHEN L. YOUNG.
